Primary Examiner — Clint A Samuel

(57) **CLAIM**

The ornamental design for a low-voltage down light, as shown and described.

DESCRIPTION

FIG. 1 is a top, front, right side perspective view of a low-voltage down light;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear side elevation view thereof; and,

FIG. 7 is a front side elevation view thereof.

The portions of the low-voltage down light shown in broken lines form no part of the claimed design.

1 Claim, 5 Drawing Sheets
